UNITED STATES PATENT OFFICE.

AXEL F. ERICKSON AND DANIEL W. SHIEK, OF AURORA, ILLINOIS, ASSIGNEES TO
ALL-STEEL-EQUIP COMPANY, OF AURORA, ILLINOIS, A CORPORATION OF ILLINOIS.

DOOR STRUCTURE.

1,895,671.

Specification of Letters Patent. Patented Nov. 1, 1932.

Application filed August 9, 1920. Serial No. 402,326.

To all whom it may concern:

Be it known that we, AXEL F. ERICKSON and DANIEL W. SHIEK, citizens of the United States, residing at Aurora, in the county of Kane and State of Illinois, have invented a new and useful Improvement in Door Structures, of which the following is a full, clear, and exact description.

This invention relates to doors and door panels especially for use in connection with lockers for the storage of clothing or wearing apparel. This application is a division in part of an application filed November 5, 1919, Serial Number 335,838.

One of the objects of this invention is to provide a door that is fabricated from a single sheet of metal formed so as to afford suitable reinforcements to provide a strong, durable and dependable structure. Another object is to provide a door structure that is not susceptible to warping or sagging from changes in temperature or rough usage.

The foregoing objects are accomplished in substantially the manner hereinafter fully described and as more particularly pointed out in the claims. Reference will now be had to the accompanying drawings forming a portion of this specification, in so much,

Figure 1 is a vertical rear elevation of a door structure fabricated in accordance with this invention.

Fig. 2 is a top plan or upper edge view of a portion thereof partly broken away and in section.

Fig. 3 is a perspective view of a fragmental portion of the reinforcing elements of the door structure prior to the turning down of the front or main plate.

Fig. 4 is a view similar to Fig. 3 showing the completed structure.

Figs. 5 to 8 are views similar to Figs. 1 to 4 respectively, and illustrate the tongues, shown projecting from the upper edges of the ribs or columns in Figs. 1 to 4, projecting from the upper edges of the flat portions upon each side of the columns.

In the drawings, similar reference characters are employed to designate the same parts throughout the several views.

The door preferably comprises a sheet of metal 5 of substantially rectangular shape and of the desired gage, that is first cut the desired shape in a flat blank. The longi-

tudinal edge portions, which comprise the vertical edges of the finished door, are folded or bent back upon themselves in the form of leaves so as to provide rounded edges 6 and these leaves lie flat against and parallel with the rear face of the plate 5 as shown at 7. A slight distance from the edges 6 these leaves are formed semi-circular to provide reinforcing ribs or columns 8 on the back of the door adjacent each vertical edge 6 thereof. The remaining portions 9 of the leaves remain flat against the rear face of the plate 5 all as shown in detail in the Figs. 2, 3, 4, 6, 7, and 8 of the drawings, so that, as will be seen, the reinforcing ribs or columns 8 are positioned intermediate the edges of the folded back edge portions or longitudinal leaves.

Suitable means are provided for further reinforcing and stiffening the door structure which are disposed at the top and bottom edges thereof for the purpose of preventing the warping and also for rigidifying the structure. These means preferably comprise the provision of the horizontally disposed projections in the form of laterally bent flanges 10 that extend along both the top and bottom edges of the main portion or body of the door plate, which flanges, when bent laterally, project inwardly a distance 35 sufficient to extend across and cover the adjacent ends of the columns or ribs 8 as seen in Figs. 2, 4, 6 and 8 of the drawings. Tongues 11 and 12, which are continuations of the bent back edge portions or leaves of the plate are provided immediately adjacent and contacting the under surface of the flange 10, and are formed from opposite side walls of the columns or ribs 8 so that their inner edges will lie adjacent the angle 95 formed by the bent over flanges 10 of the body plate. It will be understood that these flanges 10, and the tongues 11 and 12, before the edges of the door are shaped, extend outwardly from the adjacent portions 100 of the door plate in the same plane thereof, but in the fabrication of the structure the tongues 11 and 12 are first bent laterally so as to be disposed at substantially right angles to the plane of the door plate and 105 the flanges 10 are then folded or bent similarly from the front or body portion of the door plate as seen in the drawings, Figs. 3 and 7 of which illustrate the bent tongues prior to the bending over of the flanges 10. 110

2
After these flanges 10 have been properly positioned with respect to the tongues 11 and 12 the parts are spot-welded or otherwise secured together to firmly and rigidly connect them and provide a very staunch structure. It will be understood that these tongues and flanges are provided at the opposite ends of both the top and bottom edges of the door, four sets of reinforcement thus being provided.

The construction of the tongues 11 and 12 from the ribs or columns realizes the strength of these walls in the reinforcement of the flanges 10; such tongues, however, may be produced as shown in Figs. 5 to 8, which show the tongues 11^a and 12^a as projecting from the end edges of the flat portions 7 and 9 respectively of the bent back leaves. It will be understood that divers changes in the specific construction disclosed may be made without materially departing from the principles involved, as for example, the flanges and tongues may be of other shapes than herein shown, or may be riveted together. All of such modifications it will be understood are fully contemplated as coming within the scope of the appended claims, as this invention is not limited to 30 the types of structure herein shown and described.

What is claimed as new is:—

1. A door consisting of a plate the longitudinal edges whereof are folded back and provided with longitudinal columns intermediate the edges of the folded back portions, tongues at the ends of the folded back portions on each side of the respective columns, and lateral flanges on the end edges 40 of the door plate secured to said tongues.

2. A door consisting of a plate the longitudinal edges whereof are folded back upon itself, a lateral tongue at each end of each folded back portion, and a lateral flange at

each end of the plate contacting the respective tongues and secured thereto.

3. A door consisting of a plate having folded back leaves along its longitudinal edges, lateral members on said leaves, and lateral members on the adjacent portions 50 of the plate that contact and are secured to the first mentioned lateral members.

4. A door structure comprising a plate opposite edges whereof are folded back upon themselves and having columns formed in 55 the folded back portions intermediate the edges thereof, whereby flat portions are provided upon opposite sides of the columns.

5. A door structure comprising a plate opposite edges whereof are folded back upon 60 themselves, columns extending longitudinally of the folded back portions and spaced from the folded edges, and lateral flanges extending along the edges of said plate against which the ends of said columns abut.

6. A door structure comprising a plate opposite edges whereof are folded back upon themselves, hollow columns formed intermediate the edges of the folded back portions, and lateral flanges extending along 70 the transverse edges of the plate against which said columns abut.

7. A door structure comprising a plate, opposite edges whereof, are folded back upon themselves, columns formed in said 75 folded back portions, lateral flanges extending along the transverse edges of the plate, and projections below said flanges adjacent the ends of the columns to which projections said flanges are secured.

Signed at Aurora, county of Kane and State of Illinois, this sixth day of August, 1920.

AXEL F. ERICKSON.
DANIEL W. SHIEK.
